Inventor
HARRY R. LENTZ,

By *McDowell*
Attorney

UNITED STATES PATENT OFFICE

HARRY REED LENTZ, OF PHILADELPHIA, PENNSYLVANIA

MORTAR BOX

Application filed August 27, 1929. Serial No. 388,777.

My invention relates to mortar boxes, and has for an object to provide a box or container adapted to receive quantities of sand, lime, cement or other component materials 5 of mortar or the like, to be mixed therein by actuation through the mass of a suitable implement in a well known manner.

The invention consists principally in the form and configuration of the bottom surface 10 of the box, and contemplates the inclusion in a box of a novel type of bottom element which is adapted to cooperate with the usual hoe or rake to enable the constituents of the mortar or the like to be compounded more quickly 15 and efficiently and with a minimum of effort than is possible with mortar boxes of standard design.

A further object is to provide a mortar box of the character indicated which is especially adapted to be formed of sheet metal and which shall be extremely simple and inexpensive of construction, as well as durable and efficient in use.

Another object is to provide a mortar box 25 which may be constructed of a minimum number of parts and which shall nevertheless be rigid and in all respects as practically satisfactory as the more complicated boxes of the prior art.

With the foregoing and other objects in view, which will sufficiently appear as the description proceeds, the invention consists, in one form of embodiment, in the novel combination and design of parts illustrated in 30 the accompanying drawings, described herein, and hereinafter more particularly pointed out by the appended claims.

In the drawings forming part of this application for Letters Patent, whereon like reference characters indicate the same parts in the several views,

Figure 1 is a perspective view of one embodiment of my present invention; and

Fig. 2 is a vertical, longitudinal section 45 thereof.

Referring to the drawings, 1 designates the side members of a mortar box, which if desired may be constructed of sheet metal, preferably tinned or galvanized to prevent corrosion, and which are preferably flanged 50

along their upper edges, as shown at 2, to impart a greater degree of rigidity to the structure. The flanges 2 are conveniently turned inwardly to aid in preventing spilling of the contents of the box when the same are in process of being mixed together in a manner which will be presently described.

As the box is preferably made rectangular in plan, a pair of the sides 1 are employed. They are joined, by welding, soldering, brazing or equivalent means, to a bottom member 3 which, as appears from the drawing, is corrugated or waved.

It is of the essence of my present invention that the inside of upper surface of the bottom member 3 be waved, and I prefer to employ the type of wave shown in the drawing, that is, a symmetrical series of convex and concave areas, with lines of constant level extending from side to side of the box. The specific type of wave which I employ is one which may be characterized as providing a sine curve surface, i. e., a surface of which a vertical, longitudinal section (such as Fig. 2 of the drawings) exhibits a line disposed in the form of a sine curve; or, in another form of expression, a surface provided with alternate, symmetrical concave and convex areas extending transversely across the bottom in which all the highest and all the lowest points lie in two parallel planes.

The function of the curved bottom will now be briefly explained. The box is filled with sand, lime, water and other constituent materials to be mixed to form the mortar. A hoe or rake of standard design and size is then drawn through the mass, backwards and forwards, in contact with or in proximity to the bottom, in the usual manner. I have found that the curved form of the surface of the bottom shown and described herein coacts with a hoe or rake when moved across said surface to knead a plurality of different materials contained in the box into the desired intimate mixture with much fewer strokes of the hoe or rake, and consequently with the expenditure of less labor, than would be possible for the same quantity of materials if the mixing operation were performed in

the customary type of box provided with a standard plane bottom.

It will be noted by reference to the drawings that the side members 1 of the box project downwardly slightly beyond the lowest portions of the curved bottom 3 to provide base portions to support the whole structure upon the ground. It will also be noted that the end portions of the bottom 3, after being disposed in a pair of opposite, endmost concave areas, terminate in relatively long, plane, and upwardly inclined surfaces 4, 4. By this form of construction I am enabled to dispense with separate end members, the single sheet forming the bottom 3 serving also as a closure for both ends of the box. The incline of these end portions also permits the mixed material to be conveniently scooped out of the box by bucket, hoe or other convenient means.

The end portions are preferably provided with flanges 5, 5, for the purpose of increasing the rigidity of the metal, these flanges being disposed outwardly to prevent interference with the removal of material from the box.

Perforations 6, 6, may be provided in the sides 1, 1, below the bottom 3 to receive bolts, rods or the like fastening means to secure the box to fixed supports and prevent displacement of the same when in operation.

It is to be understood that while I have described a box embodying the principles of my present invention constructed of sheet metal, the invention readily lends itself to incorporation in a wooden box, or one made of any convenient material, the sheet metal construction being shown and described herein merely by way of exemplification. Other and further modifications in specific embodiments of the invention will suggest themselves to persons skilled in the art to which it relates, but all such modifications are to be regarded within the spirit of the invention and the scope and purview of the appended claims.

Having thus described my invention what I claim and desire to secure by Letters Patent is:

1. A mortar box having a substantially rigid bottom the inside or upper face of which is waved to provide a sine curve surface adapted to coact with an implement moved across said surface to knead a plurality of materials contained in the box into an intimate mixture.

2. A mortar box having a bottom formed from a single length of sheet metal bent to provide a sine curve surface adapted to coact with an implement moved across said surface to knead a plurality of materials contained in the box into an intimate mixture.

3. A mortar box having a pair of parallel sides and a substantially non-yielding bottom, the upper or inside face of the bot-

tom being waved to provide a sine curve surface, and having end portions integral with the bottom and inclined upwardly therefrom substantially to the upper edges of the sides.

4. A mortar box having a rigid bottom the inside surface of which is curved to provide alternate concave and convex areas transversely across the bottom in which all the highest points and all the lowest points lie in two parallel planes.

In testimony whereof I affix my signature.

HARRY REED LENTZ.
